UNITED STATES PATENT OFFICE.

HERMAN J. BUCK, OF ELLWOOD CITY, PENNSYLVANIA, ASSIGNOR TO MATHEWS GRAVITY CARRIER COMPANY, OF ELLWOOD CITY, PENNSYLVANIA, A CORPORATION.

CONVEYING APPARATUS.

1,407,923.

Specification of Letters Patent. Patented Feb. 28, 1922.

Application filed October 22, 1917, Serial No. 197,861. Renewed December 7, 1921. Serial No. 520,714.

To all whom it may concern:

Be it known that I, HERMAN J. BUCK, a citizen of the United States, resident of Ellwood City, county of Lawrence, State of Pennsylvania, have invented certain new and useful Improvements in Conveying Apparatus, of which the following is a specification.

My invention relates to an apparatus for conveying or transporting articles from place to place and particularly from a lower to a higher level, and the object of the invention is to provide an arrangement of carriers or conveyers and elevators by means of which an article or package may be conveyed from the lower floor of a building to the upper floor without interruption, or may be diverted for delivery at any intermediate floor.

20 A further object is to provide a conveying apparatus by means of which articles or packages may be delivered at any intermediate floor for transportation to any floor above.

25 A further object is to provide an apparatus of simple construction and one which will be strong and durable and easily installed.

Other objects of the invention will appear 30 from the following detailed description.

The invention consists generally in various constructions and combinations, all as hereinafter described and partially pointed out in the claims.

35 In the accompanying drawings forming part of this specification,

Figure 1 is a diagrammatic side view of the carrier;

Figure 2 is a plan view of the same;

40 Figure 3 is a partial sectional view, showing the delivery end of the elevator;

Figure 4 is a similar view, showing the receiving end of the elevator;

45 Figure 5 is a detail view, showing the locking means.

In the drawing, 2 represent inclined elevators, suitably supported at 3 on adjacent floors of a building. The upper end of each elevator is provided with a shaft 4 having sprockets 5 engaging chains 6. Bars 7 connect the opposite chains and engage the package or article to be transported, which rests upon a suitable floor 8. The chains are supported by suitable means, such as angle bars 9. At the lower ends of the ele-

vators the chains engage sprockets 10 on shafts 11. Comparatively short delivering and receiving carrier sections 12 and 13 are provided at the upper and lower ends of the elevators. Normally stationary carrier 60 sections 14 and 15 are provided and suitably supported at 15' upon the floors of the building. These carrier sections I prefer to designate as the receiving and delivering sections, and I may provide them on each floor 65 in connection with the elevating section of that floor, so that, as will be hereinafter more particularly described in detail, a package may be received on any floor from one of the elevators leading from the floor 70 below and a package may be delivered on any floor to an elevator section leading to the floor above.

The elevators and the gravity carrier sections 14 and 15 may be of any ordinary or 75 preferred construction, the sections 14 extending along the floor to any point thereon where it may be desired to deliver a package, while the delivering section 15 may extend to any desired point on the floor from 80 which it may be desired to send a package to a floor above. As shown in Figure 2, the receiving section of a floor is preferably substantially in alignment with the elevating section leading from the floor beneath and 85 the delivering section of that floor is preferably in substantial alignment with the elevating section leading to the floor above, and in the preferred construction the two lines of conveyers are substantially parallel and 90 adjacent.

For the purpose of connecting one line with the other and providing a continuous line from a lower to an upper floor, as when it is desired to send a package from the basement or receiving room to the top of the building, I provide switch sections 16 and 17. The former is arranged to form a continuation at the top of an elevating section, while the latter is joined to the lower end 100 of the adjacent elevating section leading to an upper floor. The switch section 16 is supported on a vertical pivot at 18 at the upper end of its elevating section and the switch section 17 is pivoted at 19 at the receiving end of the adjacent elevating section, both sections being adapted to swing in a horizontal plane on their vertical pivots. The opposite ends of the switch sections 105 from their pivots are provided with suit- 110

able anti-friction rollers 20 bearing on angle bars 21 supported by the adjacent stationary sections 14 and 15 and the switch sections are thereby adapted to swing into or 5 out of alignment with each other. The line position of the switch sections is indicated in Figure 2, where they are adjusted to connect the elevating sections of one floor with the corresponding elevating section of the 10 adjacent floor, so that a package placed on the carrier at one floor will pass up to the floor next above and continued to an upper floor without stopping, and if the switch sections on each floor are adjusted in alignment 15, the package will continue to travel until it reaches the top floor or the end of the elevating apparatus. If the attendant desires to divert a package at any floor, it is only necessary to swing a switch section 20 of that floor into alignment with the receiving section thereon and the package, instead of passing on to the floor above, will be diverted and pass onto the stationary receiving station and conveyed to any desired 25 point. I am thus able to start a package on a lower floor and pass it through without stopping to the top floor or upper level, or I may divert the package at any floor and I may also be able to deliver a package at 30 any floor to the elevating section of that floor for transportation and deliver to any upper floor.

The gravity sections may be of any preferred construction but preferably consist of 35 side rails 23, anti-friction rolls 24 and guide rails 25, suitably jointed and rigidly braced.

For the purpose of locking the switch sections 16 and 17 in their different positions I provide suitable locking means such as depressions 21' on the bars 21 for the rollers 20 to drop into, thus securing the pivoted sections in alignment with each other in position to receive a package from a delivering section or deliver one to a receiving section. Stops 20' are provided at each end 45 of the bar 21 to prevent the sections being moved beyond their required distance.

It will be understood that this apparatus 50 can be extended or carried through any number of floors in a building, that it may be made in different sizes and the switch sections may be mounted in different ways and modified in construction and still be within the scope of my invention.

55 I claim as my invention:

1. The combination with an inclined elevator section, and a gravity carrier section pivotally supported in line with the delivery end thereof, of an inclined elevator section 60 having its receiving end located out of line with and at a lower level than the delivery end of said first named elevator section, a gravity carrier section pivotally supported in line with the receiving end of the second

elevator section, and means supporting the 65 free ends of said pivoted carrier sections, and permitting lateral movement thereof, whereby said pivoted carrier sections may have their free ends arranged in line with 70 each other, causing articles to pass from the discharge end of the first named elevator to the receiving end of the second named elevator, or the free ends of said carriers may be arranged out of line with each other, permitting 75 said elevators to be independently operable, substantially as described.

2. The combination, with an inclined elevator section, and a gravity carrier section pivotally supported in line with the delivery end thereof, of an inclined elevator section 80 having its receiving end located out of line with and at a lower level than the delivery end of said first named elevator section, a gravity carrier section pivotally supported in line with the receiving end of the second 85 elevator section, a horizontal track supporting the free ends of said pivoted carrier sections, and permitting lateral movement thereof, whereby said pivoted carrier sections may have their free ends arranged in 90 line with each other, causing articles to pass from the discharge end of the first named elevator to the receiving end of the second elevator, or the free ends of said carriers may be arranged out of line with 95 each other, permitting said elevators to be independently operable, substantially as described.

3. The combination with an inclined elevator section, and a gravity carrier section 100 pivotally supported in line with the delivery end thereof, of an inclined elevator section having its receiving end located out of line with and at a lower level than the delivery end of said first named elevator section, a 105 gravity carrier section pivotally supported in line with the receiving end of the second elevator section, means supporting the free ends of said pivoted carrier sections, and permitting lateral movement thereof, whereby said pivoted carrier sections may have 110 their free ends arranged in line with each other, causing articles to pass from the discharge end of the first named elevator to the receiving end of the second named elevator, or the free ends of said carrier may be arranged out of line with each other, permitting 115 said elevators to be independently operable, and means holding the free ends of said carrier sections in either position, substantially as described.

In witness whereof, I have hereunto set my hand this 12th day of September 1917.

HERMAN J. BUCK.
